COMBINED FISH BOWL AND POLE ATTACHED SUPPORT THEREFOR

Richard Shirley, 5234 Spicer St., Toledo, Ohio

Filed Nov. 5, 1962, Ser. No. 72,380

Term of patent 14 years

(Cl. D91—2)

FIG. 1 is a view in perspective of combined fish bowl and pole attached support therefor, showing my new design;

FIG. 2 is a slightly enlarged front elevation thereof;

FIG. 3 is a side elevation thereof;

FIG. 4 is a top plan view thereof; and

FIG. 5 is a modified form thereof as shown in FIG. 1 with the fish bowl omitted for convenience of illustration, the appearance of the bottom being substantially identical with the top.

The broken lines showing of a pole in FIGS. 1 and 3 is for illustrative purposes only.

I claim:

The ornamental design for a combined fish bowl and pole attached support therefor, as shown and described.
